(57) **CLAIM**

What is claimed is the ornamental design for a hat, as shown and described.

DESCRIPTION

FIG. 1 is a front perspective view of a hat, showing a new design; and,

FIG. 2 is a front view thereof.

The broken lines immediately adjacent to the edges of the claim represent boundaries of the claim and form no part of the claimed design. All other broken lines represent environmental structure that form no part of the claimed design.
